(57) **CLAIM**

The ornamental design for a “vehicle headlight,” as shown and described.

DESCRIPTION

FIG. 1 is a front, top and right perspective view of a vehicle headlight showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a rear, top and left perspective view thereof; and,
FIG. 9 is a reference view thereof showing the vehicle headlight having a transparent cover and a headlight base. The portions in broken lines are shown for illustrative purposes only and form no part of the claimed design.
